UNITED STATES PATENT OFFICE.

GUY H. ELMORE, OF JOPLIN, MISSOURI.

COAL-SEPARATOR.

1,077,876.

Specification of Letters Patent.

Patented Nov. 4, 1913.

Application filed July 7, 1905. Serial No. 268,647.

To all whom it may concern:

Be it known that I, GUY H. ELMORE, a citizen of the United States, residing at Joplin, in the county of Jasper and State of Missouri, have invented certain new and useful Improvements in Coal-Separators, of which the following is a specification.

The object of my invention is to provide an improved apparatus for separating coal from the impurities with which it occurs, and my invention consists in the combination and arrangement of parts hereinafter described and claimed.

In the drawings Figure 1 is a top plan view of a separator embodying my invention; Fig. 2, a side elevation of Fig. 1; Fig. 3, a section on line 3—3 of Fig. 1; Fig. 4, a section on line 4—4 of Fig. 1; Fig. 5, a section on line 5—5 of Fig. 1; Fig. 6, a section 20 on line 6—6 of Fig. 1.

Reference letter A denotes jig tank compartments; B, jig tank plungers; C and C' separating sieves; D and D' discharge valves for sieves C and C'; E and E' overflow shields from sieves C and C'; F and F' sprocket chains for operating valves D and D'; G and G' dead water elevator compartments adapted to receive the discharge from valves D and D'; H an elevator compartment adapted to receive the overflow from sieve C' and communicating with a compartment I; and J, a pump for returning the water from compartment H or compartment I, to the plungers B.

35 The jig tank compartments A and plungers B are arranged on opposite sides of the sieves C and C' and serve to produce intermittent upward currents of water through the sieves, as will be readily understood by those skilled in the art.

The material to be treated is fed to sieve C from feed hopper c which is provided with a feed regulating gate c'. The action of the intermittent currents through sieve 45 C separate the coal and bone from the slate, the two former passing over shield E to sieve C', while the latter settles upon sieve C from which it is held from discharging by the valve D. Valve D is swung on a 50 shaft d which projects from the front wall of the tank and is provided with a trip arm d' carrying a roller d² adapted to engage with stops f carried by sprocket chain F. It will be seen that as each stop f engages 55 roller d², valve D will be opened to discharge slate into compartment G whence it

may be removed by means of an elevator operating therein. By placing more or fewer stops on chain F, or by increasing or decreasing the speed of the chain, the frequency of the discharge may be regulated as desired.

As seen in Figs. 1 and 2, the short shafts which carry the sprocket wheels at the upper ends of chains F and F', are connected by an intermediate sprocket chain F², whereby said shafts and their sprocket wheels, and consequently the chains F and F', are caused to maintain a definite rate or ratio of speed. Chain F' receives its motion through suitable gearing, from a driven shaft F². Thus it will be seen that both chains F and F' receive power and motion from a common source, and that, in any convenient way, as for instance, by varying the number or spacing of the stops on either chain or on the two chains, any desired ratio may be established between the opening and closing of the valves D and D'. In this way I am enabled to control accurately the amount of material delivered from the tail of each sieve, and the amount carried over the overflow shields E and E'. As the valves are opened only at intervals, it thus becomes possible to maintain on each sieve any desired depth of the lower stratum or layer of material, and thus to effect in the one machine, and by the two sieves, a separation of the material into three different classes, to wit, the slate, the bone, and 90 pure coal, in the case of coal, and corresponding products in the case of ores and other minerals.

The coal and bone passing to sieve C' are there separated one from the other, the bone settling upon the sieve and the pure coal passing on into compartment H, whence it may be removed by means of an elevator.

The valve D' is operated by chain F' in precisely the same manner as valve D to 100 discharge the bone into compartment G', whence it may be removed by means of an elevator.

The water in tank I is returned to the plungers B, by means of pump J, and pipes h, and thus may be used over and over again.

By this construction, it will be seen that the material is separated into three distinct parts, namely, slate, bone and coal, and thus a pure coal obtained.

In the foregoing description I have referred to detachable stop-carrying links as

affording means for adjusting the stops, or varying the number and relation of stops in the two chains, and this is the preferred mode of effecting such adjustment or variation. As these chains are of the ordinary separable link variety, it is obviously practicable to employ a greater or a lesser number of stop-carrying links, and thus to decrease or increase at will the distance between the stops, and to shorten or lengthen the periods between actuations of the valves; but obviously the specific means for effecting this adjustment or control is unimportant, the material point being that provision be made for varying the periods of operation of the valves D and D'.

While I have shown and described the preferred means for carrying my invention into effect, this is capable of variation without departing from the spirit of the invention. I therefore do not wish to be limited to the exact construction shown in the drawings, but

What I claim as new and desire to secure by Letters Patent is:

1. In a coal separator, the combination of a jig having a sieve; an elevator compartment at the end of the jig; a valve adapted to deliver material from the jig sieve into

the elevator compartment; a trip arm 30 adapted to operate the valve; a sprocket chain; detachable stops carried by said chain and adapted to actuate the trip arm; and means for imparting motion to said chain.

2. In a coal separator, the combination of two separating sieves; means for directing the overflow of one sieve onto the other; an elevator compartment located between the sieves and adapted to receive the discharge 40 of the first sieve; an elevator compartment adapted to receive the overflow from the second sieve; an elevator compartment adapted to receive the discharge from the second sieve; valves controlling the discharge from the sieves into their respective elevator compartments; trip arms adapted to operate said valves; sprocket chains having detachable stop-carrying links adapted to operate the trip arms; and a driving 45 shaft from which both of said sprocket chains receive motion; whereby any desired ratio may be established between the periods of opening of the respective discharge valves.

GUY H. ELMORE.
